Primary Examiner—Lucy Lieberman

[57] CLAIM

The ornamental design for a reversible inter-racial doll, as shown and described.

DESCRIPTION

FIG. 1 is a front elevational view of the preferred embodiment of the new design;

FIG. 2 is an inverted front elevational view of the preferred embodiment of the new design;

FIG. 3 is a rear elevational view of the preferred embodiment of the new design;

FIG. 4 is an inverted rear elevational view of the preferred embodiment of the new design;

FIG. 5 is a left side view of the preferred embodiment of the new design;

FIG. 6 is an inverted left side view of the preferred embodiment of the new design;

FIG. 7 is a top view of the preferred embodiment of the new design as shown in FIG. 3;

FIG. 8 is a top view of the preferred embodiment of the new design when inverted as shown in FIG. 4;

FIG. 9 is a front elevational view of an alternative embodiment of the new design;

FIG. 10 is an inverted front elevational view of an alternative embodiment of the new design;

FIG. 11 is a rear elevational view of an alternative embodiment of the new design;

FIG. 12 is an inverted rear elevational view of an alternative embodiment of the new design;

FIG. 13 is a left side view of an alternative embodiment of the new design;

FIG. 14 is an inverted left side view of an alternative embodiment of the new design;

FIG. 15 is a top view of an alternative embodiment of the new design as shown in FIG. 11; and,

FIG. 16 is a top view of an alternative embodiment of the new design when inverted as shown in FIG. 12.

The broken line showing a skirt in all of the figures is environmental only and forms no part of the claimed design.
